UNITED STATES PATENT OFFICE

CHARLES E. RUTHERFORD, OF WEST HARTFORD, CONNECTICUT, ASSIGNOR TO THE WIREMOLD COMPANY, OF HARTFORD, CONNECTICUT, A CORPORATION OF CONNECTICUT

FLEXIBLE CONDUIT FOR ELECTRICAL CONDUCTORS

Application filed October 25, 1928. Serial No. 314,969.

This invention relates to surface wiring conduits for electrical wires and more particularly to the type of conduits which have flat or substantially flat base strips and channel shaped covers, the base strips being fastened in place of use with the covers attached to the base strips in such manner as to provide an unobstructed raceway in which the wires are threaded and concealed. Previously where bends or offsets have been required to turn corners or pass over moldings, cornices, pipes or beams, it has been necessary for the installer to bend the conduits to meet the condition, which was not an easy operation and which required special tools to give the stiff channel shaped covers the proper bends without distorting them.

The object of the present invention is to provide a fitting which conforms in general shape and appearance to and can be readily connected with the common flat base strips and channel shaped covers of the running sections of the conduits, and which is so flexible that it may be easily and quickly given the necessary bend or bends to fit the turns or offsets which are met, by anyone who is installing the conduits, without special tools.

This object is attained by constructing a conduit fitting with a flat or substantially flat continuous base strip formed of a single piece of metal that can be easily bent to the required degree and connected with the running sections of the conduit, and with a cap formed of overlapping separable channel shaped scales that transversely have substantially the same shape as that of the covers of the running lengths of the conduit, which scales are capable of movement with relation to each other. Any number of these scales can be assembled together depending upon the length of the bend, and they are flexibly held together by the base strip to which they are applied.

In order to accomplish this each of the separable scales of the flexible cap may be formed of two united channel shaped sections, one of which sections is offset from or is slightly larger transversely than the other so that the offset section of one scale will fit over the inset section of the adjacent

scale when they are put together, or the scales may be formed of separable channel shaped sections, one of which is larger, transversely, than the other so that the larger will fit over the smaller, these sections having lugs or ribs that loosely interlock when assembled. The ends of the scales are curved outwardly and inwardly so as to form fingers which will fit and clasp the edges of the base strip to which they are applied and by which they are held together.

In the accompanying drawings Fig. 1 shows a side view, with a few of the channel-shaped scales cut in section, of a straight length of conduit that embodies this invention. Fig. 2 is a view of the same curved around a cornice. Fig. 3 is a side view of one of the channel-shaped scales. Fig. 4 is an end view of this scale showing a base strip therein. Fig. 5 is a side view, with parts in section, of a straight length of conduit made up of channel-shaped scales of modified form. Fig. 6 is an end view of the inner member of the modified form of scale. Fig. 7 is a side view of this inner member. Fig. 8 is an end view of the outer member of the modified form. Fig. 9 is a side view of the outer member. Fig. 10 is a view showing the modified form of conduit passed over a pipe.

In the views 1 indicates the ceiling, 2 the side wall and 3 the cornice of a room. The ends 4 and 5 of the running sections of the conduit are fixed adjacent to the cornice, and between these ends is arranged the flexible length of conduit which connects them and conceals the circuit wires 6. The length of flexible conduit of the form first illustrated has a base 7 which is a strip of flexible or pliable metal cut to the required length and that is substantially flat but is usually slightly curved in cross-section. Applied to and held together by this base strip are the channel-shaped scales, each of which preferably has a section 8 of one size, transversely, and an integral section 9 that is substantially the same shape but is slightly smaller transversely, so that the smaller section of one scale will fit loosely within the larger section of the adjacent scale. The ends 10 of these

sections are curved outwardly and inwardly so that they will receive and clasp the edges of the base strip.

Whereas in the form above described each scale is made of two channel-shaped sections which are integral, in the modified form of conduit illustrated the scales are made in two separable channel-shaped sections 11 and 12 which transversely are substantially the same shape, but one, 11, is sufficiently larger than the other, 12, to enable the former to be loosely fitted over the latter. The smaller section 12 has outwardly extending ribs 13 along its edges and the larger section 11 has inwardly extending lugs 14, the lugs engaging the ribs when the larger section is fitted over the smaller section, to retain the sections from endwise separation. These sections have curved inner edges 15 shaped to clasp the edges of the flexible or pliable base strip 16.

With the first form the necessary number of scales to produce the required length of conduit are assembled by inserting the smaller sections within the larger sections and then sliding these thus assembled upon the base strip. With the second form the required number of larger sections are thrust over two adjacent smaller sections and the length thus formed is slipped upon the base strip. Both forms provide a flexible length of conduit that is capable of being bent internally or externally, or both, so that it may be curved around a cornice, about pipes, or other projections or irregular surfaces which are encountered, and readily joined to the ends of the running lengths of conduit.

The scales of this flexible length of conduit in transverse section are similar to the cross-sectional shape of the running lengths so that when the conduit is completed the whole will appear harmonious. The base strips may be made of indefinite length and cut into lengths required to meet the conditions which arise, and the scales are stamped to shape in indefinite numbers and the necessary number applied to the base strip by the manufacturer to complete the conduit. The base strips are connected with the ends of the running lengths of the conduit in the usual way.

The invention claimed is:

1. A flexible surface wiring conduit for electrical conductors, comprising a continuous metallic base strip and a plurality of channel-shaped overlapping metallic scales movably connected together and loosely applied to and held from separation by the base strip.

2. A flexible surface wiring conduit for electrical conductors, comprising a continuous metallic base strip and a plurality of channel-shaped overlapping metallic scales movably connected together and having

curved ends formed to grasp the edges of said base strip.

3. A flexible surface wiring conduit for electrical conductors, comprising a continuous metallic base strip and a plurality of channel-shaped metallic scales applied to the base strip, said scales being formed of two sections, one of which is larger than and is shaped to loosely fit over the other section.

4. A flexible surface wiring conduit for electrical conductors, comprising a continuous metallic base strip and a plurality of channel-shaped metallic scales applied to the base strip, each of said scales being formed of a larger section and an integral smaller section whereby the scales may be loosely assembled with relation to each other on the base strip with the smaller section loosely fitted within the larger section of the adjacent scale.

5. A flexible surface wiring conduit for electrical conductors, comprising a continuous metallic base strip, and a plurality of channel-shaped independent metallic scales applied to and held together by the base strip with the edge of each scale loosely extending within the edge of the adjacent scale.

6. A flexible surface wiring conduit for electrical conductors comprising a plurality of overlapping metallic U-shaped sections and a continuous metallic base strip engaging the ends of said sections and loosely retaining them in movable relation with each other.

CHARLES E. RUTHERFORD.
